J. SCHUTTEN

OIL CAN

Filed Oct. 3, 1923

UNITED STATES PATENT OFFICE.

JOSEPH SCHUTTEN, OF LOS ANGELES, CALIFORNIA.

OIL CAN.

Application filed October 3, 1923. Serial No. 666,376.

To all whom it may concern:

Be it known that I, JOSEPH SCHUTTEN, a citizen of the United States, residing at Los Angeles, in the county of Los Angeles and State of California, have invented a new and Improved Oil Can, of which the following is a specification.

The invention relates to oil cans and especially to that type of oil can in which it is sought to provide means for effecting the same discharge of oil therefrom when the oil reservoir is full as when the same is practically exhausted.

In the usual manufacture of oil cans, especially those types wherein is provided a centrally disposed exhausting tube, or in some types, a centrally disposed oil discharge effecting mechanism, it is practically impossible to effectively discharge oil from the can after the supply contained therein has become partially exhausted.

Therefore it is the object of the invention to provide an oil can in which means is provided whereby the oil is effectively discharged therefrom at all times when a quantity of oil is contained therein, regardless of the smallness of the quantity or the position of the can during such discharge.

In addition to the before mentioned object, and also in combination therewith, it is an object of the invention to provide an effective means for discharging oil from the can under pump action.

With the above and other objects in view that will hereinafter appear, the invention further resides in those novel details of construction, combination and arrangement of parts, all of which will be first fully described, then be specifically pointed out in the appended claims and illustrated in the accompanying drawing, in which:

Figure 1 is a central vertical section of the invention, the parts being shown at the normal position.

Figure 2 is a view similar to Figure 1, the parts being shown at an oil discharge position.

In the practical development of my invention, I provide a main body portion or oil receptacle 1, which may be constructed in almost any shape desired but is preferably constructed in the approximately half spherical form illustrated and to include the usual threaded filling neck 2.

A threaded closure cap 3 is provided and the same has formed centrally thereof and

integrally therewith a pendent cylindrical portion 4 adapted to project down into the body 1 to form a pump casing or chamber, as is clearly illustrated in the figures of the drawing. The bottom end of this pendent portion is stamped in the manner illustrated at 5 so as to form a proper bearing for loosely holding the ball 6 so as to form a ball and socket joint.

An inlet tube 7 is provided and includes an angled portion adapted to pass through the ball 6 for communicating with the chamber formed by the portion 4 in any of the positions which the tube may take in the manner later to be described. The inlet end of the tube 7 is provided with a ball and check housing or inlet tip 8 in which is provided a common type of spring pressed back check valve ball 9.

By reference to the drawing, it will be observed that the center of the ball and socket joint 5—6 is at or adjacent to the center of the curvature of the dome portion of the body 1 and that the relation of the inlet tube 7 with the ball and socket joint is such that the inlet tip 8 lies at a point at the bottom of the reservoir formed by the body 1 when the can is in the normal position illustrated in Figure 1 and the tube is permitted to change its position in accordance with any position in which the can may be held while discharging the oil therefrom, see, for example, Figure 2. Thus, the inlet tip 8 is always directed to that part of the can into which the deepest portion of the quantity of oil contained therein gravitates to, regardless of what position the can is held in, this being possible by reason of the effect of gravity on the tube 7 and the provision of the ball and socket joint.

A plunger body 10 is provided which is adapted to be slidable vertically through the bushing 12 secured in the upper end of the portion 4 and this plunger body 10 has formed integrally therewith an enlarged head 11 which may be finger engaged for forcing the plunger downwardly against the action of the spring 20 which is interposed between the head 11 and the closure cap 3.

A pair of leather washers 13 are secured to the end of the plunger body 10 through the medium of the screw cap 14 which threads into the counterbore 15 formed in the body 10, the latter merging with the oil passage 16 formed in that body and which is adapted to cooperate with a similar oil

passage 17 in the cap 14 for permitting oil to flow therethrough from the chamber formed by the casing portion 4 when the spring pressed ball valve 18 permits such 5 oil passage.

When the plunger head 11 is forced inward, as is indicated in Figure 2, thereby forcing inward the plunger 10-13, the back check valve 9 serves to prevent the forcing 10 of oil out of the chamber formed by the casing 4 while the valve 18 is forced open to permit the discharge of the oil contained in that chamber out through the passages 17-16 into and through the usual discharge 15 spout 19, as is shown in Figure 2. When the head 11 is again released and forced outwardly by the spring 20, the valve 18 automatically closes, thereby causing the plunger 10-13 to draw in a new charge of oil into 20 the chamber provided by the casing 4, the ball valve 9 being automatically opened during this action.

By reason of the ball and socket arrangement 5-6 the inlet tip 8 will always gravitate so as to be at the point of greatest oil 25 depth regardless of the position in which the can may be held, it being even possible for the tube 7 to gravitate to the approximate vertical position so that the oil may be 30 removed from the body or oil receptacle 1 almost to the last drop and, by reason of the fact that a charge of oil is first drawn into 35 the chamber formed by the casing 4 and then expelled therefrom, the removal of the oil from the body portion is just as effective when the oil is partially exhausted from the body as when the body is full.

From the foregoing description, taken in connection with the accompanying drawings, 40 it is thought the construction, operation and advantages of my invention will be readily understood by those skilled in the art to which the invention relates.

What I claim is:

45 1. In a device of the class described, the combination with a fluid receiving body of substantially half spherical shape, of a spout for discharging the contents of said body, a rigid member through which fluid is adapted 50 to be conveyed to said spout within the body, said member including a fluid entrant end, means for universally-swivelly mounting said member within said body in cooperative relation to said spout so that said entrant end may follow the curvature of said body in any direction and be automatically presented to the greatest depth of the fluid 55 as the position of the body is changed in effecting the fluid discharge.

60 2. In a device of the class described, the combination with a fluid receiving body, a spout for discharging the contents of said body, a member through which fluid is adapted to be conveyed to said spout within 65 the body, said member including a fluid

entrant end, a universal joint cooperatively connecting said member with said spout so that said entrant end may follow the contour of said body in any direction and be automatically presented to the greatest 70 depth of the fluid as the position of the body is changed in effecting the fluid discharge.

3. In a device of the class described, the combination with a fluid receiving body of substantially half spherical shape, of a member through which fluid is adapted to be drawn from said body, the said member being ball and socket mounted within the body with the center of the ball and socket 75 joint at a point closely adjacent to the center of curvature of the said body.

4. A device of the class described comprising a fluid receiving body, a fluid chamber within the body, a member cooperative with the chamber through a ball and socket joint and through which fluid is adapted to be drawn into the chamber, and means for effecting the drawing of fluid into said chamber from the body and for discharging the fluid therefrom out of said chamber.

5. A device of the class described comprising a fluid receiving body, a fluid chamber within said body, a member cooperative with the chamber through a ball and socket joint and through which fluid is adapted to be drawn into the chamber, means for effecting the drawing of fluid into said chamber from the body and for discharging the fluid therefrom out of said chamber, a valve cooperative with said chamber for permitting discharge of fluid only, and a valve cooperative with the member for permitting an indrawing of the fluid only.

6. In a device of the class described the combination with a fluid receiving body of substantially half spherical shape, a fluid chamber within the body, a member cooperative with the chamber through a ball and socket joint and through which fluid is adapted to be drawn into the chamber, the center of the ball and socket joint being at a point closely adjacent to the center of curvature of the said body, and means for effecting the drawing of fluid into said chamber from the body and for discharging the fluid therefrom out of said chamber.

7. A device of the class described, comprising a fluid receiving body, a fluid chamber within said body, a member cooperative with the chamber through a universal joint connection and through which fluid is adapted to be drawn into the chamber, and means for effecting the drawing of the fluid into said chamber from the body and for discharging the fluid therefrom out of said chamber.

8. In a device of the class described the combination with a fluid receiving body, a spout for discharging the contents of the

body, a force feed mechanism for ejecting the contents of the body through the spout, said mechanism including a pendent cylindrical portion, a member through which 5 fluid is adapted to be conveyed through said pendent cylindrical portion, and a universal joint connection between said member and said cylindrical portion, all being arranged whereby the entrant end of said 10 member may follow the contour of said body in any direction and be automatically presented to the greatest depth of the fluid as the position of the body is changed in effecting the fluid discharge.

15 9. In a device of the type stated, the combination with a fluid receiving body of substantially half spherical shape and including a filling neck opening; of a closure cap for said opening and including a chamber forming portion, a member having a ball and 20 socket joint with said chamber forming portion at a point closely adjacent the center of curvature of the body and through which fluid is adapted to be drawn from the body into the chamber, a pump plunger movable 25 in said chamber for effecting a drawing of fluid into the chamber when moving in one direction and for forcing fluid out of said chamber when moving in the opposite direction, and check valves controlling the 30 said fluid passage.

JOSEPH SCHUTTEN.
